UNITED STATES PATENT OFFICE.

CHRISTIAN RÖPKE, OF BREMEN, GERMANY.

COUNTING FRAME.

Application filed July 26, 1927, Serial No. 208,561, and in Germany June 7, 1927.

This invention relates to a counting frame and consists in the provision of a vertical row of horizontal shafts, and a plurality of independently rotatable counting members 5 threaded on each shaft, the counting members being adapted to hold detachable counting elements in the form of plates, objects or the like.

The counting members are adapted to engage the shaft resiliently and to be retained thereon in different angular positions, and detachable grouping members for the counting members are provided.

Fig. 1 of the accompanying drawing represents a front view of the counting frame,

Fig. 2, an end view of the same,

Fig. 3, a perspective view on an enlarged scale of one of the counting members according to one construction,

Fig. 4, an end view of the frame showing the attachment of the grouping member,

Fig. 5, a perspective view on an enlarged scale of a modified form of counting member,

Fig. 6, a perspective view of yet another form, and

Fig. 7, a side view of the same counting member complete with its counting elements.

The counting frame is composed of a vertical row of horizontal shafts such as 1 and 2 secured by screws 4 to supporting frames 3 and 3^a. Threaded on each shaft is a plurality of counting members which are independently rotatable, each shaft being fitted with detachable counting elements such as representations of actual objects chosen from within the range of experience of the child, or plates bearing figures or numbers.

Means are provided for retaining the counting members on the shafts with one of these objects or plates in view while the others are more or less concealed. For this purpose the shafts are preferably of polygonal cross-section and formed with as many sides as the counting members have numeral plates or objects, the counting members being preferably in the form of clips adapted to grip the shaft resiliently and to find a resting place on each side of the shaft. In the illustrated arrangement the shafts have four sides, and the counting members 5 are adapted to carry four plates 6.

The counting members may be of various constructions. Fig. 3 shows a member composed of two resilient plates 5^a which are formed across the center with angular bends

to fit the supporting shaft, the plates being interconnected by rivets 8 which are distanced from the bent center portions so as to allow the latter to yield and snap over the corners of the shaft. The outer portions of the plates are bent apart so as to form diverging arms 5^b between which the plates 6 are clamped. For connection to the plates 6, each arm has at its outer end a bead 9 which is bent back into S-shape so as to form two channels 9^a and 9^b in each of which a plate can be supported, as shown in Fig. 3.

As an alternative construction, a counting member may be formed out of a single metal stamping, as shown in Fig. 5. The stamping 10 is formed across the center with angular bends 14 two of which are set in one direction and one in the other, longitudinal slits being made at opposite sides of the center bend so as to allow the center portions to yield. Longitudinal slits 11 are also made from the ends of the stamping so as to form a central arm 12 which is bent in one direction and lateral arms 13 which are bent in the opposite direction. The arms are beaded as previously described.

Another alternative construction is shown in Figs. 6 and 7 and consists of two angular plates 15 and 16 one of which is slotted across the bend to receive the bent portion of the other plate. The intermeshing plates are applied to the shaft whereon they are retained by resilient tongues 17 which are formed on the slotted plate and arranged so as to bear against and support the other plate. In this instance the arms are formed with beads 18 behind which one set of diametrically opposite number plates 6 may be inserted, the other set of number plates being formed with hooked ends adapted to engage over the beads.

The counting members may be divided on the frame into groups for which purpose grouping members 7 are provided. Such grouping members may consist of a bar the ends of which are bent back at an acute angle to form supporting arms 7^a and 7^b. One of these arms is forked for engagement with the upper shaft 1, the other arm being placed loosely against the shaft 2.

I claim:

1. A counting device comprising a shaft, a plurality of independently rotatable counting members, each provided with resilient means to grip the shaft and maintain it in any position in its orbit of movement there-

- on, and a plurality of counting elements carried by each counting member.
2. A counting device comprising a vertical shaft, a plurality of independently rotatable counting members mounted on the shaft, each counting member having a resilient hub adapted to grip the shaft to hold the member in any position in its orbit of movement thereon, and a plurality of counting elements carried by each counting member.
3. A counting device comprising a shaft of rectangular cross-section, a plurality of independently rotatable counting members mounted on the shaft, each counting member having a resilient hub of angular cross-section to grip the shaft and maintain it in any position in its orbit of rotation thereon, and a plurality of counting elements carried by each counting member.
4. A counting device comprising a shaft, a plurality of independently rotatable counting members mounted on the shaft, each counting member having a resilient hub to grip the shaft and hold it fixed at points in its orbit of rotation thereon, and each member also having a series of arms, and counting elements detachably engaging said arms.
5. A counting device comprising a shaft, a plurality of independently rotatable counting members mounted on the shaft, each counting member having a resilient hub to grip the shaft and hold it in any one of a plurality of positions, and each member also having a plurality of arms provided with terminal engaging members, and counting elements detachably engaging said terminal engaging members of the arms.
6. A structure as claimed in claim 1 wherein in the shaft is of polygonal cross-section and the resilient hubs of the counting members are of corresponding form.
7. A structure as claimed in claim 1 wherein in the shaft is of polygonal cross-section and wherein each counting member is provided with a resilient hub to grip the shaft and carries as many counting elements as there are sides on the shaft.
8. A counting device comprising superposed vertical shafts, counting members rotatably mounted on said shafts, and a spacing device for separating the members on the shafts into groups, said spacing device extending between and engaging the shafts.
9. A structure as claimed in claim 1 wherein the counting members are composed of plates having beaded edges for engagement with the detachable counting elements.
10. A structure as claimed in claim 1 wherein the counting members are composed of plates having beaded edges for engagement with the detachable counting elements, the counting members having hooked edges for engagement with the beads.
11. A structure as claimed in claim 1 wherein the counting members are composed of plates having beaded edges for engagement with the detachable counting elements, the beads being of S-shaped cross-section, the counting elements being composed of plates adapted to engage in said beads from both sides.

In testimony whereof I affix my signature.

CHRISTIAN RÖPKE.
